UNITED STATES PATENT OFFICE.

LOUIS DUFEK, OF TACOMA, WASHINGTON.

DESIGN FOR A LAMP-GLOBE.

53,031.

Specification for Design.

Patented Mar. 4, 1919.

Application filed January 31, 1918. Serial No. 214,781. Term of patent 7 years.

To all whom it may concern:

Be it known that I, LOUIS DUFEK, a citizen of the United States, residing at Tacoma, in the county of Pierce and State of Washington, have invented a new, original, and ornamental Design for Lamp-Globes, of which the following is a specification, reference being had to the accompanying drawing, forming part thereof.

The figure is an elevated view of a lamp globe, showing my new design. The upper portion of the globe is colored or ground to act as an ornamental shade.

I claim:

The ornamental design for a lamp globe, as shown.

LOUIS DUFEK.
